OSCAR HOLT, OF ROTHsay, MINNESOTA.

POTATO-CUTTING MACHINE.

1,274,042.

Specification of Letters Patent. Patented July 30, 1918.

Application filed November 1, 1917. Serial No. 199,699.

To all whom it may concern:

Be it known that I, OSCAR HOLT, a citizen of the United States, residing at Rothsay, R. F. D. #3, in the county of Wilkin 5 and State of Minnesota, have invented certain new and useful Improvements in Potato-Cutting Machines, of which the following is a specification.

This invention relates to potato cutting 10 machines, and more particularly to a machine for cutting seed potatoes.

One of the main objects of the invention is to provide a machine of simple construction and operation which may be produced 15 at comparatively small cost for cutting potatoes into suitable pieces for seed purposes. A further object is to provide a machine so constructed as to accommodate potatoes of different sizes and provide substantially uniform pieces for seed. A further object is 20 to provide a machine in which the means for cutting the potatoes will act to automatically discharge the potatoes from the machine after being cut. Further objects will appear from the detailed description.

In the drawings:

Figure 1 is a side view of a machine constructed in accordance with my invention.

Fig. 2 is a section taken on line 2—2 of 30 Fig. 1.

Fig. 3 is a section on line 3—3 of Fig. 1.

Fig. 4 is a section on line 4—4 of Fig. 2.

Fig. 5 is an underneath view of the cutting block and blades carried thereby.

The body of the machine is in the form 35 of a supporting stand having the legs 1, 2, 3, and 4, side beams 5, and cross-beams 6. A longitudinally extending foot lever 7 is rockably mounted intermediate its ends on 40 a cross-bar 8 secured in the legs 2 and 4. The forward end of this lever is provided with a central slot 9 which receives the lower end of a link 10 pivotally secured therein by a pin 11 passed through aligned 45 bores in the link and lever. The upper end portion of this link is slotted longitudinally to provide a clamp in which is loosely secured a stirrup 12 the upper ends of the arms of which are rigidly secured to the 50 cross bar of a yoke 13 rockably mounted in a U-bracket 14 secured to the upper ends of the legs 2 and 4. A coil tension spring 15 is secured at one end to the link 10 and at the other end to foot lever 7. By this construction, when the inner end of the foot le-

ver is depressed, the outer end of yoke 13 will be raised and, when the foot lever is released, spring 15 will act to return the lever and the link to their initial positions.

A cutting block 16 is pivotally secured 60 between the inner ends of the arms 17 of yoke 13. This block is normally disposed in a substantially vertical plane, the longitudinal center line of the block being in the same vertical plane as the center of the slot 65 or opening 18 extending between the leaves 19 and 20 of a receiving hopper, which are rockably mounted in the side beams 5. The outer edge of leaf 19 is secured to a transverse shaft 21 rockable in the side beams, 70 the outer edge of leaf 20 being secured to a similar shaft 22. Shaft 21 is provided, at one end, with an integral rearwardly directed crank 23 disposed at a right angle to the shaft, this crank being in alinement with an 75 oppositely directed crank 24 formed integral with shaft 22. The ends of the cranks 23 and 24 are bent to form eyes through which are secured the ends of a coil tension spring 25. This tension spring acts 80 to normally hold the cranks in substantially horizontal position so as to maintain the leaves 19 and 20 of the receiving hopper in raised position. By this construction, when the block 16 is depressed for the cutting operation, the leaves 19 and 20 will be 85 forced downward and outward as indicated in Fig. 4 of the drawings so as to discharge from the receiving hopper the potatoes which have been cut, simultaneously with 90 the cutting operation.

As will be noted more clearly from Fig. 2 of the drawings, the leaves of the receiving hopper are provided, contiguous with their inner edges and in their upper faces, with 95 coöperating recesses which form a substantially circular receiving recess 26, an intermediate substantially elliptical recess 27, and a smaller elliptical recess 28. The leaves are further provided with transverse 100 aligned slots extending from the inner edge of each leaf which form slots 29, 30, 31, and 32 extending transversely of the hopper from the central opening or slot 18 and at right angles thereto. The central slot 18 105 and the transverse slots communicating therewith are adapted to receive the cutting members 18^a, 29^a, 30^a, 31^a, and 32^a which are secured in the block 16 and project below the same to form a cutting grid.

In using this machine, the small potatoes will be placed in the end elliptical recess 28, the medium size potatoes in recess 26, and the large potatoes in the central recess 27. 5 When the block 16 is depressed, the potato in recess 26 will be cut into four sections, the large potato in recess 27 into eight sections, and the small potato in the recess 28 into two sections. By this arrangement, 10 I insure that the potatoes will be divided into pieces of substantially uniform size regardless of the size of the potato being cut. For this reason, this machine is well adapted for use in connection with potatoes 15 which have not been sorted or graded and is, therefore, very practical in that it avoids the necessity of grading the potatoes preliminary to cutting them for seed. After the potatoes have been cut, the block continues its downward movement and engages the upper surfaces of the leaves 19 and 20 of the receiving hopper so as to force the same downward and outward thus discharging the cut potatoes from the hopper which 25 may be received in any suitable receptacle suspended beneath the machine. When the potatoes have been thus cut and discharged from the machine, the pressure on the foot pedal 7 is removed, and spring 15 acts to 30 return the cutting mechanism and the operating means therefor to their initial positions.

To insure proper operation of the block 16, a guide member 33 is secured to one side beam 5. This guide member projects vertically adjacent one end of the block and receives a guide pin 34 secured in the block and slideable between the arms of member 33. The pin 34 and member 33 coöperate 40 to maintain the block in vertical position during its movement toward and away from the receiving hopper. A stop 35 is secured in the member 33 for engagement by the guide pin 34 and serves to positively limit 45 the upward movement of the block.

To permit adjustment of the cutting mechanism, the yoke 13 is provided in each arm 17 with a series of spaced apertures for receiving the pivot rod 36, and link 10 is provided with a series of spaced apertures 50 for receiving the pin 11. By this means, the cutting mechanism may be adjusted so as to insure accuracy of operation thereof.

It will be evident that there may be slight 55 changes in the construction and arrangement of the different parts of my invention without departing from the field and scope of the same, and I intend to include all such variations, as fall within the scope of the 60 appended claims, in this application in which a preferred form only of my invention is disclosed.

What I claim is:

1. In potato cutting machines, a receiving 65 hopper provided with a plurality of closure

members movable downwardly so as to open the hopper, means for normally holding said members in raised position, and a cutting device movable toward and away from the hopper so as to cut potatoes placed in 70 the same, said cutting device being movable into engagement with the closure members so as to open the hopper and discharge the cut potatoes therefrom.

2. In potato cutting machines, two rockably mounted leaves having their inner edges adjacent so as to form a receiving hopper, said leaves being provided in their upper faces with recesses for receiving potatoes to be cut, means for normally holding 75 the leaves in raised position, a block mounted above said leaves and movable toward and away from the same, a cutting device carried by the block and projecting from the lower face thereof for cutting potatoes 80 placed within the recesses of the leaves, and means for actuating said block, the block being movable into engagement with said leaves so as to depress the same and discharge the cut potatoes. 85

3. In potato cutting machines, two leaves rockably mounted at their outer edges and having their inner edges adjacent, said leaves being provided in their upper faces with recesses for receiving potatoes, means for normally holding the leaves in raised position, a block mounted above said leaves and movable toward and away from the same, and a cutting member carried by said block and positioned to pass between the two leaves 100 when the block is depressed so as to cut potatoes placed in the recesses of the leaves and permit the block to engage said leaves so as to rock the same downward and outward and discharge the cut potatoes therefrom, said blocks being movable into engagement with the leaves so as to depress the same. 105

4. In potato cutting machines, two leaves rockably mounted at their outer edges and having their inner edges disposed in parallel spaced relation, said leaves being provided in their upper faces with recesses of different sizes for receiving potatoes to be cut, the leaves being further provided with 110 transverse slots extending from the inner edges thereof across the recesses, the number of slots for the recesses varying, means for normally holding the leaves in substantially horizontal position, a block mounted above said leaves and movable toward and away from the same, the center of said block being positioned in alignment with the space between the inner edge of the leaves, a cutting device carried by the 115 block and projecting beyond the lower face thereof consisting of a longitudinally extending cutting member positioned at the center of the block and transversely extending cutting members spaced to correspond 120

with the transverse slots of the leaves, and means for actuating said block.

5. In potato cutting machines, a supporting frame, spaced transverse shafts rockably mounted therein and provided at one end with oppositely directed cranks, a tension spring secured to the free ends of said cranks, supporting leaves secured at their outer edge to said shafts and having their 10 inner edges disposed in spaced relation, said leaves being provided in their upper faces with coöperating recesses which form recesses of different sizes for receiving potatoes to be cut, said leaves being further provided with transverse slots extending from the inner edges thereof crossing the recesses, a block mounted above the leaves and movable toward and away from the same, a cutting device carried by said block and projecting beyond the lower face thereof consisting of longitudinally and transversely disposed cutting elements so arranged as to be operated through the space between the

leaves and the transverse slots in the leaves, and means for actuating said block. 25

6. In potato cutting machines, a hopper provided with a plurality of closure members movable into position to open the hopper and discharge cut potatoes therefrom, said closure members being provided in their 30 upper faces with recesses of different sizes for receiving potatoes to be cut so as to support the potatoes placed therein in position over the spaces between the two said members, and a cutting knife movable toward 35 and away from the said closure members and operative between the same so as to cut potatoes placed therein when the knife is depressed.

In testimony whereof I affix my signature 40 in presence of two witnesses.

OSCAR HOLT.
